UNITED STATES PATENT OFFICE.

SAMUEL J. ADAMS, OF DETROIT, MICHIGAN, ASSIGNOR OF THREE-FOURTHS TO MONROE ROSENFELD, JACOB BROWN, AND ARTHUR BROWN, ALL OF SAME PLACE.

DEVICE FOR HOLDING TELEPHONES.

SPECIFICATION forming part of Letters Patent No. 403,316, dated May 14, 1889.

Application filed March 13, 1889. Serial No. 303,081. (No model.)

To all whom it may concern:

Be it known that I, SAMUEL J. ADAMS, of Detroit, in the county of Wayne and State of Michigan, have invented a new and useful 5 Improvement in Devices for Holding Telephones, of which the following is a specification.

My invention consists in a device for holding telephones, hereinafter fully described 10 and claimed.

Figure 1 is a perspective showing my invention in position. Fig. 2 is a plan view of the chain holding device. Fig. 3 is a side elevation of a portion of the device; and Figs. 15 4 and 5 are bottom plan views, with some of the parts omitted.

S represents the call-bell attachment of a Bell telephone, k being the hook for holding the receiving-telephone R, J the cord connecting the receiver R with the line, and i representing the transmitter. With these my invention has nothing to do, its object being merely to support the receiving-telephone R in convenient position for the user.

25 A represents a plate adapted to be secured to the wall above the telephone, and carrying thereon a lug, C, and a toothed arc, E.

D represents an arm whose inner end is curved and adapted to lie between lug C and 30 arc E, and is pivoted on the pin B, which passes through lug C, arm D, and arc E. The outer end of arm D is enlarged into a jaw, H, to the inner surface of which is secured a curved clamp, J, by the pin a passing through 35 the jaw H, and encircled by the light spiral spring b, Figs. 4 and 5, whereby the clamp J is made adjustable. The under side of arm D is grooved, as shown at g in Fig. 4, and is provided just back of the jaw H with an inclined surface, e.

40 U represents a bar adapted to lie in the groove g on the under side of arm D, and enlarged at its outer end into a jaw, I, similar to jaw H, and provided with a clamp, K, similar to clamp J. These clamps K and J may be both fastened to their respective jaws I and H, so as to simply turn on the pivot which connects the clamp to the jaw, or may both be made adjustable, as shown in the case

of J, or one may be adjustable like j and the other merely turn like K. The other end of bar U is formed with a pointed dog, T, to engage with the teeth in arc E, and the bar is further provided with an inclined shoulder, f, adapted to engage with the shoulder e on 55 bar D.

G represents a bolt, which passes through jaws H and I back of the clamps J K, and c represents a spiral spring encircling bolt G between the jaws and constantly tending to 60 force said jaws apart.

F represents a lever fulcrumed on bolt G, and having two oppositely-inclined planes or wedges, W and Z, on its inner side, adapted to bear against the outer surface of arm D and 65 jaw H, and thereby to draw the jaw I toward the jaw H when lever F is moved.

M represents a rod of wood or metal adapted to fit within the clamps J K and to be securely held in said clamps.

N represents a bridge secured to rod M near its lower end, and provided with a cleat, O, with which a cord or chain, L, whose end is attached to the end of lever F, may be engaged to hold said cord taut.

70 Q represents a clip jointed at the point P to the lower end of rod M, adapted to clasp and hold the receiving-telephone R. This joint is of the common kind which swings only in one direction.

75 V is a stop-pin in the under side of bar D, which operates against an inclined surface in bar U to disengage dog T from the teeth in arc E.

The operation of my invention is as follows: 80 The receiver R is supposed to be supported by the hook k, the joint P permitting the clip Q to be turned into a horizontal position for this purpose. The cord L being slack, the clamps J and K hold the rod M loosely, and 85 the dog T is thrown out of engagement with the teeth on arc E by the action of spiral spring c, which presses jaw I away from jaw H, and, through the action of stop-pin V on the inclined surface on bar U, throws said bar 90 U slightly forward. The rod M is therefore free to slide vertically, and the clamps J K are free to permit said rod to swing forward

or back. In answering a telephone-call the user lifts the receiver R from the hook k, moves the receiver to a point where it comes opposite the ear, this being permitted by the 5 free motion of bar D and rod M, and then draws cord L taut and secures it by clamping it into cleat O. This swings lever F, so that its inclined planes W and Z draw the jaw I toward the jaw II, thus firmly clamping rod 10 M between the clamps J K, and at the same time forcing dog T into engagement with the teeth of arc E, thus locking both the bar D and the rod M and retaining the receiving-telephone R in position. To restore the receiver R, it is only necessary to disengage cord L from cleat O, when the machine becomes 15 again flexible and may be moved at will.

What I claim as my invention, and desire to secure by Letters Patent, is—

20 1. In combination with a receiving-telephone, a rod having on one end a clip to engage with the telephone, a pair of movable jaws adapted to engage with said rod, a swinging arm carrying said jaws, an arc and a locking-dog at the pivotal end of the swinging arm, and 25 a lever connected with said arm and adapted to simultaneously lock said arm and jaws, substantially as shown and described.

2. In a telephone-supporting device, the combination, with the supporting-plate A, of 30 the pivoted arm D, toothed arc E, jaws H and I, rod M, lever F, and cord L, substantially as shown and described.

3. In combination with the supporting-plate A, carrying the toothed arc E, the pivoted 35 arm D, having thereon the fixed jaw II, the movable bar U, carried by the arm D, having on one end the jaw I and on the other end a dog, T, the movable clamps J and K, carried by said jaws H and I, and the lever F, provided with the opposite inclined planes W and Z and fulcrumed on a bolt, G, connecting said jaws, substantially as shown and described.

4. In a telephone-supporting device, the 40 combination of the fixed jaw II and movable jaw I with the lever F, having thereon a cam adapted to draw the movable jaw toward the fixed jaw, the cord L, connected with said lever, and the rod M, carrying the cleat O, substantially as shown and described.

SAML. J. ADAMS.
